truck of a well known type comprising a frame 9 supported on truck wheels 10 adapted to run along a mine trackway 11. Supported on the truck frame at the rear of the turntable 2 is a 5 motor 12, herein preferably of the reversible electric type, connected through a plural speed transmission mechanism, generally designated 13, to the truck wheels and through connections to be hereinafter described to the devices for elevating 10 and tilting the turntable 2. Mounted at the rear end of the truck is a usual reeling device 14 for the power conductor cable 15 through which current is supplied to the motor 12 and a main driving motor 16 mounted on the rotatable turntable 15 structure. Also mounted on the truck frame is an electrical control apparatus 17 for the motors 12 and 16.

Referring to the turntable mounting structure for the cutting mechanism, it will be noted that 20 supported for vertical and universal tilting adjustments relative to the truck frame is a supporting frame 18, herein in the form of an annulus or ring having attached thereto a plurality of, herein in three, depending brackets 19, the lower ends of 25 which are shaped to engage, respectively, with up-standing guide members 20, herein in the form of screw pedestals, which are secured to the truck frame. Fixed to these depending brackets 19 are internally threaded nuts 21 (see Fig. 5) which are 30 threadedly engaged with vertical screws 22 rotatably supported at their upper ends by the up-standing guide members 20 and at their lower ends in step bearings 23 formed in bearing brackets 24 attached to the bottom of the truck frame. 35 It will be noted that the nuts 21 are so connected to the feet of the depending brackets as to permit a slight relative rocking movement between the parts. The three sets of screws and guide members constitute upright supports for the annular supporting frame or ring 18, and the latter 40 can be adjusted vertically in parallelism or angularly to change its angle in altitude by suitable rotation of the screws. Mechanism for separately or simultaneously rotating the screws will be 45 later described. The turntable 2 supported by the annular frame 18 is in the form of a circular casting which constitutes the main frame of the cutting mechanism. This casting forms the turntable rotatable about the center of the ring 18 50 and is guided for rotative movement in the ring by a depending annular flange 25 fitting the interior periphery of the ring 18 and by a radial flange 28 overlying the top surface of the ring.

Motor operated devices are employed for rotating the turntable 2, and herein comprise the 55 motor 16, which is herein preferably of the reversible electric type suspended beneath the turntable casting within the lateral limits of the annular supporting frame 18 in the manner shown. 60 The power shaft 27 of this motor is horizontally disposed and extends transversely across the turntable beneath the top surface of the latter, and has fixed thereto a bevel pinion 28 meshing with a bevel gear 29 fixed to a vertical shaft 30 suitably 65 journaled within the turntable casting. Fixed to and driven by the shaft 30 is a spur gear 31 meshing with a spur gear 32 suitably fixed to a vertical shaft 33, herein arranged parallel with the shaft 30 and likewise suitably journaled within 70 the turntable casting. Secured to the shaft 33 is a worm 34 meshing with a slow speed worm wheel 35 connectible, by a multiple disc clutch 36 of a usual design, to a horizontal shaft 37. Fixed to and driven by the shaft 37 is a worm 38 meshing, as shown in Fig. 3, with a worm wheel 39

rotating about a vertical axis and suitably journaled within the turntable casting. As shown in Fig. 4, this worm wheel drives a vertical shaft 40 connectible, by a clutch 41, to a spur gear 42 supported by the shaft and meshing with the 5 teeth of a circular rack 43 formed on the inner periphery of the annular supporting frame 18; the gear 42 when released from the shaft 40 being freely rotatable on the shaft. Also meshing with the spur gear 31 is a spur gear 44 secured to a vertical shaft 45 arranged parallel with the shafts 30, 33 and disposed at the opposite side of the shaft 30 from the shaft 33, as shown in Fig. 3. Driven by and rotatable with the shaft 45 is a 10 worm 46 meshing with a fast speed worm wheel 15 47. This worm wheel is connectible by a multiple disc clutch 48 similar to the clutch 36 to the shaft 37. It will thus be seen that when the clutch 41 is connected and one or the other of the disc 20 clutches 36, 48 is applied, the turntable 2 may be rotated relative to the annular supporting frame 18 to swing the cutting mechanism about the turntable axis at either a relatively high positioning speed or a relatively low cutting speed. The teeth of the worm gears 38, 39 are self-locking and lock automatically the turntable against rotation when the clutches 36, 48 are released. The turntable release clutch 41, that is the clutch 25 for freeing the turntable from the self-locking worm gearing, comprises, as shown in Figs. 4 30 and 6, clutch plungers 49 guided within slots 50 formed in the shaft 40. Rotatably mounted within the shaft 40 is a clutch operating shaft 51 having an operating handle 52 and formed on its lower end a pair of grooves 53. When the shaft 35 40 51 is in the position shown in Fig. 4, the clutch plungers are projected within notches 54 formed in the gear 42, thereby locking the gear to the shaft 40. When the shaft 51 is turned to bring notches 53 in registry with the grooves 50 the 45 clutch plungers are free to slide inwardly thereby to release the gear 42 from the shaft 40. The clutch 41, when released, cuts loose, so to speak, the turntable from its rotating mechanism, thereby permitting the turntable to rotate freely relative to the annular supporting frame 18.

Now referring to the kerf cutting mechanism 4, and more particularly to the improved adjustable supporting structure therefor it will be observed that formed integral with the box-like extension 50 frame or arm structure 5 overhanging the annular frame 18, and depending from the arm structure is a circular frame 55 arranged in a substantially vertical position and rigidly braced with respect to the arm by means of vertical webs 55 56. As illustrated, secured to the circular frame 55 is an annular retaining and bearing sleeve 57 having an inwardly directed flange 58. Between this flange and shoulder 59 formed on the circular frame 55 there is rotatably mounted a sleeve 60 60 which herein forms a rotatable support or neck for the rotatable head 6. This bearing sleeve 60 is secured to a projecting neck frame 61 on which the adjustable supporting structure 3 for the cutting mechanism 4 is mounted, as will later be 65 described.

The mechanism for effecting rotation of the cutter head frame 61 about the axis of the neck herein comprises a bevel gear 62 fixed to the upper end of the shaft 38 and meshing with a bevel gear 63 keyed to a horizontal shaft 64. The shaft 64 extends radially with respect to the turntable axis and is suitably journaled within the turntable casting and circular frame 55. Fixed to the shaft 64 is a spur gear 65 meshing 70 75

with a spur gear 66 keyed to a parallel shaft 67 likewise suitably journaled within the turntable casting. Also fixed to the shaft 67 is a bevel pinion 68 meshing with reverse bevels 69 and 70 (see Fig. 16). These reverse bevels are selectively connectible by friction clutches 71 and 72 respectively to a transverse shaft 73 suitably journaled within the turntable casting. These clutches are provided with any suitable operating means including a shipper yoke 74 actuated by an operating rod 75 having an operating handle 76. Suitably secured to the shaft 73 is a worm 77 meshing with a worm wheel 78 fixed to a horizontal shaft 79 arranged parallel with the shaft 64 and likewise suitably journaled within the turntable casting. Fixed to the forward end of the shaft 79 (see Fig. 3) is a spur gear 80 meshing with an internal gear 81 herein formed integral with the rotatable support 69 secured to the cutter head frame 61. It will thus be seen that upon suitable application of the friction clutches 71, 72 the cutter head frame 61 may be rotated about the neck axis in one direction or the other to position the cutting mechanism in a plurality of intersecting planes about the neck axis. The worm gearing 77, 78 is of the self-locking type and when the clutches are released, automatically locks the cutter head frame against rotation about the axis of the neck, thereby maintaining the cutting mechanism in any of its adjusted positions about the neck axis.

Now referring to the improved adjustable supporting structure 3 for the cutting mechanism, it will be observed that formed on the rotatable neck frame 61 and extending forwardly therefrom are projections 85, 85 which are parallel to each other and parallel to and equidistant from the axial line of the neck. In each of said projections is a bearing 86 in alignment with the other of said bearings on a line which is perpendicular to and intersects the axial line of the neck. In said bearings 86, 86 is mounted a transverse hinge shaft 87. Forward of the neck structure is a single swingable supporting arm 88 which constitutes the sole supporting connection between the revoluble head structure and the cutting mechanism 4 and having at its rear end projections 89, 89, each of which overlaps the inner face of one of the walls 85 of the neck structure, as shown in Fig. 7. These projections 89, 89 are mounted on the bearing sleeves carried by the projections 85, 85, and the hinge shaft 87 extends through the projections 89 and 85 within the bearings to form journals for the arm 88, said journals being on an axial line which is perpendicular to and intersects the axial line of the neck. At its forward end the arm 88 has a pair of parallel projections 90, 90 each of which is in approximately the plane of the corresponding projections 89, and each of these projections 90 overlaps the inner face of one of a pair of projections 91, 91 formed on a support 92 on which the kerf cutter is mounted. Supported within each of the projections 90, 90 is a bearing sleeve 93, and mounted within these bearing sleeves is a transverse hinge shaft 94 arranged parallel to the shaft 87. These bearing sleeves in which the shaft 94 is supported project outwardly through the side arms 91, 91 formed on the cutter support 92 and form a pivotal mounting for the cutter support 92 as hereinafter described. Pivotally mounted on the cutter support 92 about an axis perpendicular to the axial line of the neck, in the manner hereinafter described, is an elongated plane cutter bar 95 carrying on its margin

an endless cutter bit carrying cutter chain 96, this cutter bar being swingable about its axis in planes parallel to the neck axis and in planes including the neck axis.

The driving connections between the motor 16 and the cutter chain 96 herein include the bevel gearing 28, 29, vertical shaft 30, bevel gearing 62, 63 and the horizontal shaft 64. Keyed to the forward end of the shaft 64 is a spur gear 100 meshing with a spur gear 101 keyed to a 10 shaft 102 herein extending along the axis of the neck and suitably journaled within the frames 55 and 61. Fixed to the forward end of the neck shaft 102 is a bevel gear 103 meshing with and driving a bevel gear 104 loosely mounted on the 15 hinge shaft 87. On the arm 88 are two bearings 105, 105 which are on an axial line which intersects the axial lines of the hinge shafts 87 and 94, and the axial line of the neck. In said bearings 105 is journaled a transmission shaft 106 which 20 has fixed thereto at its rear end a bevel gear 107 meshing with and driven by the bevel gear 104, as shown in Fig. 7. Fixed to the forward end of the shaft 106 is a bevel gear 108 meshing with and driving a bevel gear 109 fixed to the 25 hinge shaft 94. Journaled within the cutter support 92, as shown in Figs. 7 and 8, is a shaft 110 having fixed thereto at its rear end a bevel gear 111 meshing with and driven by the bevel gear 109. Fixed to the forward end of the shaft 30 110, as shown in Fig. 11, is a bevel gear 112 meshing with a bevel gear 113 keyed to a shaft 114 suitably journaled within the cutter support 92 and arranged with its axis perpendicular to the shaft 110 and the axial line of the neck. 35 Keyed to the shaft 114 is a chain sprocket 115 which engages and drives the cutter chain 96 in the manner well understood in the art. The cutter support 92 comprises a body 116 and a cap member 117 which is suitably secured to the body. 40 The pair of projections 91, 91 is formed on the body 116. The body extends forwardly and has a bearing 118 which receives one end of the shaft 114, as shown in Fig. 11. The cap member extends forwardly and has a bearing 119 in alignment with the bearing 118 and also receives the shaft 114. Swivelly mounted on the bearings 118, 119 to swing about the axis of the shaft 114 is a bar hanger frame or support 120 which carries the cutter bar 95. It will thus be seen that 50 the cutter bar 95 is pivoted to swing on the axial line of the shaft 114.

The mechanism for swinging the cutter bar herein comprises a worm wheel 121 loosely surrounding the bearing 118 and journaled on the 55 cylindrical bearing engaging portion 122 of the hanger support 120, as shown in Fig. 11. This worm wheel rests against a supporting plate 123 and bears against the horizontal bar support, and is adapted to be engaged with the cutter support 60 by a latch mechanism to be hereinafter described. It will thus be seen that the worm wheel 121 is arranged concentric with the shaft 114, and meshing with this worm wheel is a worm 124 fixed to a transverse shaft 125. The shaft 125 is 65 suitably journaled in bearing sleeves 126 supported within boss-like projections 127, 127 formed integral with the side arms 91, 91. The mechanism for rotating the worm in either of opposite directions to swing the cutter bar in 70 opposite directions about its pivot at a slow speed appropriate for cutting herein comprises a bevel gear 128 fixed to the hinge shaft 94 and meshing with reverse bevels 129, 130 loosely journaled on an inclined shaft 131. The shaft 131 75

is suitably journaled within a gear housing 132 secured to the side of the cutter support 92. Splined to the shaft 131 is a jaw clutch member 133 which is operable to connect selectively the 5 reverse bevels to the shaft 131. Keyed to the shaft 131 is a worm 134 (see Fig. 13) meshing with a worm wheel 135 keyed to the shaft 125 which drives the worm 124 meshing with the bar swinging worm wheel 121. It will thus be seen 10 that the cutter bar may be swung in its plane about its pivot and that the cutter chain may be driven irrespective of the adjustment of the supporting structure about the neck axis or the plane of operation of the cutter bar.

15 The latch mechanism for locking the hanger support 120 to the worm wheel 121 or for releasing the hanger support for free swinging movement about the axis of the shaft 114 herein comprises a latch 136 pivotally mounted at 137 20 on the hanger support 120. The cap plate 123 is provided with a notch 138 for receiving the latch and allows said latch to rest between two teeth of the worm wheel 121. Suitable means 25 139 is provided for maintaining the latch 136 in its locking position, this means 139 being readily releasable to permit swinging of the latch into its unlocked position. It will thus be seen that when the latch is in its locking position, as shown in Fig. 11, and the worm wheel 121 is 30 rotated through the mechanism above described, the cutter bar may be swung with the worm wheel at a slow cutting speed. When the latch 136 is swung downwardly and released from the teeth of the worm wheel and the notch 35 138 in the cap plate, the cutter bar may be freely swung relative to the worm wheel. This latch mechanism may be the same as that described in the patent to Oldroyd 1,460,076.

The mechanism for adjusting the improved 40 supporting structure 3 to position the cutter bar in parallel planes while maintaining the cutter bar parallel to a line parallel to the neck axis or for tilting the cutter bar out of parallel relation with the neck axis comprises worm racks 45 140 formed on the projections 85, 85 of the revoluble head structure. Meshing with these worm racks are parallel worms 141, 141 keyed to parallel shafts 142, 142 suitably journaled within the arm 88, and in the present construction arranged 50 with their axes perpendicular to the axial line of the hinge shaft 87. Keyed to the shafts 142, 142 are worm wheels 143, 143 (see Fig. 9) which mesh with worms 144, 144 keyed to a transverse shaft 145 likewise suitably journaled within the 55 arm 88. Keyed to the shaft 145 intermediate its ends is a worm wheel 146 meshing with a worm 147 loosely mounted on the transmission shaft 106. This worm is connectable to the shaft 106 by a suitable clutch 148 having suitable shifter mechanism 149 including a transverse shaft 158 carrying at its opposite ends operating handles 151 located at the opposite sides of the arm 88. Also formed on the projection 91, 91 on the cutter support 92 are worm racks 152, 152 with which 60 mesh worms 153, 153 keyed to parallel shafts 154, 154 suitably journaled within the forward end of the arm 88. Keyed to these shafts are worm wheels 155, 155 with which mesh worms 156, 156 keyed to a transverse shaft 157 herein arranged 65 parallel with the shaft 145 and likewise suitably journaled within the arm 88. Fixed to this shaft intermediate its ends is a worm wheel 158 with which meshes a worm 159 (see also Fig. 8) loosely journaled on the transverse shaft 106 and connectable to the shaft by a clutch 160 similar to 70 the clutch 148 and having similar operating mechanism including handles 161 arranged adjacent the handles 151 heretofore described. From the foregoing description it will be evident that when the worms 147, 159 are connected to the shaft 106 and the shaft 106 is connected to the motor, the worms 141, 141 meshing with the worm racks 140 and the worms 153 meshing with the worm racks 152 are simultaneously driven, causing the arm 88 to be swung about the axis of the hinge shaft 87 in one direction while the cutter support 92 is swung about the axis of the hinge shaft 94 in the opposite direction, the speeds of adjustment being so proportioned that as the supporting arm and cutter support are swung simultaneously about their respective axes the cutter bar 95 is maintained at all times parallel to a line parallel to the axial line of the neck. It will be evident that when the clutch 143 is disconnected and the clutch 160 connected the cutter support 92 may be swung about the axis of the hinge shaft 94 while the arm 88 remains stationary, thereby enabling the cutter bar to be tilted out of parallelism with the neck axis about an axis transverse to its length. It will also be 25 evident that when the clutch 160 is connected and the clutch 148 released the supporting arm 88 may be swung about its axis while the cutter support 92 remains stationary as to movement about its axis. The worms 141, 141 and 153, 153 30 meshing with the worm racks on the revoluble head frame and cutter support respectively are self-locking and maintain automatically the arm and cutter support in their different positions of adjustment about the axes of the hinge shafts. 35

Now referring to the mechanism for driving the truck wheels, it will be noted that fixed to the power shaft of the motor 12 is a worm 165 (see Fig. 14) meshing with a worm wheel 166 rotatably mounted on a transverse shaft 167 suitably journaled within a frame 168 suitably secured to the truck frame. This worm wheel may be operatively connected to the shaft 167 by means of a friction clutch 169 having suitable operating mechanism including a hand lever 170. 40 Fixed to this transverse shaft 167 is a brake drum 171 which is engaged by a brake band 172 also arranged to be controlled by the hand lever 170. When this hand lever is swung in one direction the clutch is applied and in the opposite direction the brake is applied and the clutch released. Journaled on this shaft 167 is a spur gear 173 connectible with the shaft by a jaw clutch member 174 splined to the shaft, and this gear meshes with a spur gear 175. The spur gear 175 is connected to a transverse shaft 176 suitably journaled within the frame 168. Keyed to the shaft 167 is a spur pinion 177 meshing with a spur gear 178 secured to a transverse shaft 179 (see Fig. 15) arranged parallel with the shaft 167. 50 Splined to the shaft 179 is a slideable pinion 180 adapted to mesh with a spur gear 181 keyed to a sleeve 182 herein formed integral with the spur gear 173. If desired, operating mechanism may be provided for the clutch member 174 and the 55 sliding pinion 180 so that when one is connected the other is released. As illustrated, secured to the shaft 176 is a chain sprocket 183 connected by an endless chain connection 184 to a chain sprocket secured to the rear truck axle. The 60 front and rear truck axles are connected together by a usual chain and sprocket connection 185. It will thus be seen that when the jaw clutch 174 is shifted to connect the spur gear 173 to the shaft 167 and the pinion 180 is out 65 70 75

- of mesh with the spur gear 181, the truck wheels may be driven at a relatively high speed from the motor 12 through worm gearing 165, 166, friction clutch 169, shaft 167, spur gearing 173, 175 and the chain and sprocket connections 183, 184, 185. It will also be evident that when the jaw clutch 174 is in its released position and the spur pinion 180 is slid into meshing engagement with the spur gear 181, the truck wheels 10 may be driven at a relatively slow speed appropriate for cutting through the reduction gearing 171, 172, 180 and 181. Upon reversal of the motor 12 the truck wheels may be driven to propel the apparatus in the reverse direction at either 15 a relatively high or a relatively low speed.
- The mechanism for driving the turntable elevating and tilting screws 22 herein comprises a bevel pinion 186 (see Fig. 14) journaled on the shaft 167 and connectible to the shaft by the 20 clutch member 174. This bevel pinion meshes with a bevel gear 167 fixed to a vertical shaft 188 suitably journaled within the frame 168. Keyed to the shaft 188 is a chain sprocket 189 which engages and drives an endless transmission chain 190 arranged beneath the truck frame. Idler sprockets 191 and 192 serve to guide the 25 chain 190 relative to chain sprockets 193 rotatably mounted, as shown in Fig. 5, upon each of the screws 22 at its lower end, and these sprockets 30 are driven by the endless chain 190. As shown, the sprockets 193 have formed thereon clutch teeth 194 adapted to engage with similar teeth on clutch members 195 splined to the lower end 35 of the screws. The screws extend downwardly through openings in the top plate of the truck frame and the clutch members 195 are each provided with a groove 196 in engagement with an arm 197 attached to a vertical operating shaft 198. The shafts 198 extend through the top plate 40 of the truck frame and are each provided with a handle 199 by which the movement of the clutch members may be controlled. It will thus be seen that when all the clutches 195 are in a position to connect the chain sprockets 193 to 45 the screws, the latter may be simultaneously rotated to move the turntable 2, together with the cutting mechanism supported thereby, into different elevated positions relative to the truck frame. It will also be noted that by releasing certain of these clutches and connecting certain others the screws may be rotated to effect tilting movement of the turntable about a horizontal axis to change its angle in altitude relative to the truck frame.
- The mode of operation of the improved mining apparatus is as follows: The apparatus is propelled along the mine trackway at a relatively high transport speed through the truck wheel driving gearing 165, 166, 173, 175 driven by the 50 motor 12, it being understood at that time the adjustable supporting structure 3 and the cutting mechanism 4 are swung upwardly from the full line position shown in Fig. 2 to a position wherein the cutter bar 95 is disposed above the level of the trackway. When the working face is reached, the high speed truck wheel drive is disconnected from the motor 12 by releasing the friction clutch 169 and the sliding clutch 174. If it is desired to make a swinging cut at or near the level of 55 the mine floor in front of the end of the trackway, the controlling clutches 148 and 160 for the adjustable supporting structures are connected, and upon running of the motor 16 in the proper direction, the supporting arm 88 is swung downwardly about the axis of the hinge shaft 87 while 60 the cutter support 92 is simultaneously swung upwardly about the axis of the hinge shaft 94 until the parts assume the position indicated in full lines in Fig. 2, the clutches 148, 160 thereafter being released. With the cutter bar thus disposed the operator connects the proper reverse bevel 129, 130 of the bar swinging mechanism to the shaft 131 and the cutter bar is swung in its plane through the bar swinging gearing 134, 135, 124, 121 under the control of the clutch 133, the cutter 10 bar swinging laterally about its pivot relative to the cutter support 92 from the central position shown in Fig. 1 laterally to a position wherein the tip end of the bar is disposed adjacent the right hand rib of the entry, the bar swinging 15 clutch 133 thereafter being released. The apparatus is then propelled forwardly along the trackway until the cutter bar assumes the proper position relative to the coal face and thereafter the operator applies the brake 171, 172 to hold 20 the apparatus stationary on the mine trackway. When the parts are thus disposed, the operator connects the proper reverse bevels 129, 130 in driving relation with the motor and the cutter bar is swung transversely in its plane from right to 25 left across the front end of the trackway at a relatively low cutting speed to make a swinging cut beneath the coal. When the tip end of the bar reaches a position adjacent the left hand rib the bar swinging clutch 133 is released, and upon 30 release of the brake 171, 172 the apparatus is propelled rearwardly along the mine trackway at a low speed through the truck driving gearing 165, 166, 177, 178, 180, 181 and 173, 175 driven by 35 the motor 12 to move the cutter bar away from the coal face. The cutter bar is thereafter swung into its central position shown in Fig. 1, and upon connection of the clutches 148, 160 and reversal of the motor 16, the adjustable supporting structure 4 is swung upwardly to move the cutter bar 40 into its transport position above the level of the trackway. The apparatus is then propelled rearwardly along the mine trackway under the propulsion of the high speed truck driving gearing 165, 166, 173, 175 driven by the motor 12. 45
- If it is desired to cut a horizontal kerf at or near the level of the mine bottom outside and below the level of the mine trackway in accordance with the arcweld method, the operator applies the friction clutch 48 of the fast speed turntable 50 rotating mechanism, thereby rotating the turntable 2, together with the cutting mechanism supported thereby, from the central position shown in Fig. 1 to the full line position indicated at A in Fig. 17 wherein the pivot of the cutter bar 95 55 lies outside the trackway. During this rotary movement of the turntable relative to the truck, the cutter bar 95 may be swung simultaneously about its pivot in the opposite direction relative to the cutter support 92 under the control of the clutch 133 of the bar swinging mechanism until the tip end of the cutter bar assumes the full line position shown in Fig. 17 adjacent the right hand rib at a less angle than the angle of the arm 88 60 relative to the rib. When the parts are thus disposed with the bar pivot lying outside the mine trackway, the controlling clutches 148, 160 for the adjustable supporting structure are connected 65 thereby moving the cutter bar at or near the level of the mine floor as shown in full lines in Fig. 2, the clutches 148, 160 thereafter being released. At that time, the cutting mechanism is connected in driving relation with the motor and the cutter chain 96 is rapidly circulated about the 70 margin of the cutter bar 95. The pinion 180 of 75

the slow speed truck driving mechanism is then slid into meshing engagement with the gear 181 and upon application of the friction clutch 169 the truck wheels are driven to propel the apparatus bodily in the forward direction along the mine trackway at a relatively slow cutting speed, sumping the cutter bar 95 beneath the coal until it assumes the dotted line position indicated at B in Fig. 17. The friction clutch 169 is then released and the brake 171, 172 set. The operator then applies the friction clutch 36 of the slow speed turntable rotating mechanism and the turntable 2, together with the cutting mechanism supported thereby is rotated at a slow cutting speed to effect horizontal swinging movement of the cutter bar in its plane across the coal face to make a horizontal cut thereunder. During the initial rotative movement of the turntable 2 the cutter bar 95 is swung about its pivot under the control of the clutch 133 in the reverse direction until the parts assume a straight line position indicated at C in Fig. 17 wherein the cutter bar extends radially with respect to the turntable axis. When the cutter bar assumes the dotted line position indicated at D in Fig. 17 with its tip end adjacent the left hand rib and the swinging cut beneath the coal has been completed, the cutter bar is again swung about its pivot in a direction opposite from the direction of turntable rotation under the control of the clutch 133 while rotation of the turntable is continued, the turntable and cutter bar swinging simultaneously in opposite directions at that time until they assume an angular position with the cutter bar disposed at a less angle relative to the left hand rib than the angle of the arm 88 relative thereto, as indicated in dotted lines at E in Fig. 17. The clutches 36 and 133 and the brake 171, 172 are then released, and upon application of the friction clutch 169 of the truck wheel drive and the reversal of the motor 12 the apparatus is propelled bodily rearwardly along the mine trackway at a low cutting speed, moving the cutter bar from the dotted line position indicated at E in Fig. 17 to the dotted line position indicated at F in that figure, withdrawing the cutter bar from beneath the coal. After the completion of the cut beneath the coal the parts are again returned to their central transport position with the cutter bar disposed in an elevated position above the mine trackway.

A horizontal kerf may be cut at or near the level of the mine roof simply by applying one or the other of the friction clutches 71, 72 of the head rotating mechanism to effect rotation of the head frame 61 about the neck axis, thereby moving the cutter bar through an arc of a circle from the full line position shown in Fig. 2 to its opposite horizontal position above the head axis, as indicated in dotted lines in Fig. 2. To vary the elevation of the cutter bar when thus disposed, the adjusting mechanism for the supporting structure 3 may be connected in driving relation with the motor 16 thereby to effect swinging of the cutter bar upwardly or downwardly to the elevation desired. When the cutter bar is thus positioned it is sumped in, swung transversely in its plane and withdrawn from the coal in accordance with the usual arcwll method of cutting. By adjusting the supporting structure 3 the cutter bar may be disposed to cut kerfs in any desired horizontal planes between the mine roof and the mine floor.

To effect a slabbing cut, the turntable 2 is rotated to move the adjustable supporting structure 3 laterally until the cutter bar assumes the

position shown in Fig. 21 with the bar pivot outside the trackway. The adjusting mechanism for the supporting structure may then be connected in driving relation with the motor 16 to move the cutter bar into the desired horizontal position. When the cutter bar is disposed in the position shown in Fig. 21 the slow speed truck drive is connected in driving relation with the truck wheels and the apparatus is propelled rearwardly along the mine trackway to effect a slabbing cut 10 in the coal.

It will be noted that during any of the horizontal cutting operations described above, for instance when it is desired to cut on a rolling or uneven bottom, or a pitching coal seam, the cutter bar may be tilted to change its angle in altitude simply by rolling the cutter head about its axis relative to the turntable structure and by swinging the cutter support 92 upwardly and downwardly in the desired direction about the 20 axis of the hinge shaft 94. The cutting mechanism may also be universally tilted relative to the truck to change its angle in altitude simply by disconnecting certain of the elevating screws 22 from the motor 12 while others are rotated, thereby causing the turntable to be tilted relative to the horizontal. For instance if it is desired to tilt the tip end of the cutter bar downwardly, this may be accomplished by disconnecting the clutches from the front elevating 30 screws 22 while the rear elevating screw is connected to the motor 12, thereby causing the rear edge of the turntable to be elevated. Conversely, if it is desired to tilt the tip end of the cutter bar upwardly, the rear elevating screw may be disconnected from the motor while the front elevating screws are rotated, thereby causing the forward edge of the turntable to be tilted upwardly.

A shear or vertical cut may be inserted in the 40 coal face simply by applying one or the other of the reverse frictions 71, 72 of the head rotating mechanism, thereby rotating the head frame 61 about the neck axis to bring the cutter bar 95 into a position to swing vertically. When the 45 cutter bar assumes the full line position indicated at G in Fig. 22 with the tip end of the cutter bar adjacent the mine roof, the apparatus is propelled bodily along the trackway, sumping the cutter bar within the coal until it assumes the 50 dotted line position indicated at H in that figure. The cutter bar swinging mechanism is then connected, and the cutter bar is swung downwardly in its plane from the position indicated at H in Fig. 22 to the dotted line position indicated at I 55 in that figure. The apparatus is then propelled rearwardly along the trackway to move the cutter bar from the position I to the position indicated in dotted lines at J in Fig. 22, withdrawing the cutter bar from the coal face. The cutter bar is sumped in, swung downwardly in its plane and thereafter withdrawn from the coal face in the manner similar to that described above in connection with horizontal cutting in accordance with the arcwll method. It will be 60 noted that by rotating the head frame about the neck axis the cutter bar may be moved through an arc of a circle into shearing positions at either side of the neck axis, and when the cutter bar is thus disposed the adjustable supporting 65 structure may be swung horizontally about the axis of the hinge shaft 87 to move the cutter bar from a center cutting position indicated at K in Fig. 20 laterally to the position indicated at L in Fig. 19, the turntable 2 remaining stationary 70

75

at that time. If it is desired to increase the shearing range of the apparatus the adjustable supporting structure 3 may be swung laterally about the axis of the turntable, and upon suitable adjustment of the cutter support 32, the cutter bar may be positioned adjacent the rib as indicated at M in Fig. 18, the supporting arm 33 being disposed in alinement with the arm structure of the turntable at that time. It will thus be seen that the cutter bar may be disposed in any desired shearing position between the ribs of the entry including a position at the center of the entry and positions at either rib of the entry.

To effect a vertical or shearing cut in the mine wall when the apparatus is supported and guided by a curved trackway, the apparatus is operated in the following manner: With the cutter bar 95 in shearing position the turntable 2 is rotated to move the cutting mechanism laterally until the tip end of the cutter bar engages the rib of the entry. The turntable is then locked against rotation and the cutter bar is swung upwardly to a position adjacent the mine roof. When the parts are thus disposed the apparatus is propelled along the curved trackway at a low speed to cause the tip end of the cutter bar to penetrate the coal. The turntable clutch 41 is then released and the turntable is permitted to rotate freely relative to the truck as the apparatus is propelled bodily along the trackway, and as a result, as the apparatus moves along the curved trackway the cutter bar is sumped within the coal in the manner well known to those skilled in the art, the free rotation of the turntable relative to the truck as the latter moves along the trackway preventing binding of the cutter bar in the kerf. The cutter bar is then swung downwardly in its plane and withdrawn from the coal to complete the shearing cut.

As a result of this invention, it will be noted that an improved coal mining apparatus is provided having improved adjustable kerf cutting mechanism whereby horizontal kerfs may be cut at or near the level of the mine floor outside and below the level of the mine trackway, and vertical kerfs may be cut at any desired location between the ribs of the entry. It will further be noted that by the provision of the improved adjustable supporting structure for the kerf cutting mechanism, the cutter bar may be positioned to cut kerfs in any desired horizontal planes between the mine roof and the mine floor or in any desired vertical planes between the ribs of the entry. It will also be evident that by the provision of the improved adjustable supporting structure and the tiltable turntable mounting for the kerf cutting mechanism the cutter bar may be universally tilted to change its angle in altitude thereby to accommodate itself to a rolling or uneven bottom or pitching coal seam. It will still further be noted that an improved coal mining apparatus is provided wherein the adjusting mechanism for the kerf cutting mechanism is extremely flexible, it being possible to operate the apparatus as a mounted bottom cutter, top cutter, center cutter, shear cutter and slabbing machine and to operate the apparatus to make shear cuts while the apparatus is supported and guided by a curved trackway, thereby enabling the apparatus to accommodate itself to practically every mining condition encountered within the normal working range of a track cutting machine. These and other uses and advantages of the improved min-

ing apparatus will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a portable base, a supporting structure swingable horizontally relative to said portable base, a support mounted on said supporting structure to rotate relative thereto about a horizontal axis, an arm structure pivotally mounted on said support to swing relative thereto, a kerf cutter support swingably mounted on the outer extremity of said arm structure, said cutter support being swingable relative to said arm structure to move the kerf cutter into angularly related cutting planes, and motor operated, operator controlled means for swinging said cutter support relative to said arm structure while the latter remains stationary as regards swinging movement relative to said first support.

2. In a mining apparatus, a portable base, a supporting structure swingable horizontally relative to said portable base, a support mounted on said supporting structure to rotate relative thereto about a horizontal axis, an arm structure pivotally mounted on said support to swing relative thereto, a kerf cutter support swingably mounted on the outer extremity of said arm structure, said cutter support being swingable relative to said arm structure to move the kerf cutter into angularly related cutting planes, and motor operated, operator controlled means for independently swinging said arm structure relative to said support and said cutter support relative to said arm structure.

3. In a mining apparatus, a portable base, a supporting structure swivelly mounted on said base to swing horizontally relative thereto about a vertical axis, a support mounted on said supporting structure to swing horizontally relative thereto about a parallel axis, a kerf cutter support swivelly mounted on the outer extremity of said support to swing relative thereto about an axis parallel with said axes, a kerf cutter pivotally mounted on said cutter support to swing in a vertical plane relative thereto about a horizontal axis, and motor operated, operator controlled means for swinging said cutter support relative to said first support while the latter remains stationary as regards swinging movement relative to said supporting structure.

4. In a mining apparatus, a portable base, a supporting structure swivelly mounted on said base to swing horizontally relative thereto about a vertical axis, a support mounted on said supporting structure to swing horizontally relative thereto about a parallel axis, a kerf cutter support swivelly mounted on the outer extremity of said support to swing relative thereto about an axis parallel with said axes, a kerf cutter pivotally mounted on said cutter support to swing in a vertical plane relative thereto about a horizontal axis, and motor operated, operator controlled means for independently swinging said first support relative to said supporting structure and said cutter support relative to said first support.

5. In a mining apparatus, a portable base, a

- supporting structure swivelly mounted on said base to swing horizontally relative thereto about a vertical axis, a support mounted on said supporting structure to swing horizontally relative thereto about a parallel axis, a kerf cutter support swivelly mounted on the outer extremity of said support to swing relative thereto about an axis parallel with said axes, a kerf cutter pivotally mounted on said cutter support to swing in a vertical plane relative thereto about a horizontal axis, and motor operated, operator controlled means for independently swinging said first support relative to said supporting structure and said cutter support relative to said first support, said first support being swingable relative to said base about the axis of said supporting structure or relative to said supporting structure about said parallel axis.
6. In a mining apparatus, a portable base, a supporting structure swivelly mounted on said base to swing horizontally relative thereto about a vertical axis, a support mounted on said supporting structure to swing horizontally relative thereto about a parallel axis, a kerf cutter support swivelly mounted on the outer extremity of said support to swing relative thereto about an axis parallel with said axes, a kerf cutter pivotally mounted on said cutter support to swing in a vertical plane relative thereto about a horizontal axis, and motor operated, operator controlled means for independently swinging said first support relative to said supporting structure and said cutter support relative to said first support, said first support being swingable relative to said base about the axis of said supporting structure or relative to said supporting structure about said parallel axis and said cutter support being swingable relative to said first support while said latter support remains stationary.
7. In a mining apparatus, a portable base, a supporting structure swivelly mounted on said base to swing horizontally relative thereto about a vertical axis, a support mounted on said supporting structure to swing horizontally relative thereto about a parallel axis, a kerf cutter support swivelly mounted on the outer extremity of said support to swing relative thereto about an axis parallel with said axes, a kerf cutter pivotally mounted on said cutter support to swing in a vertical plane relative thereto about a horizontal axis, said cutter support being swingable relative to said first support while the latter remains stationary, and motor operated, operator controlled means for swinging said cutter support relative to said first support and for swinging said kerf cutter in its plane.
8. In a mining apparatus, a portable base, a supporting structure swivelly mounted on said base to swing horizontally relative thereto about a vertical axis, a support mounted on said supporting structure to swing horizontally relative thereto about a parallel axis, a kerf cutter support swivelly mounted on the outer extremity of said support to swing relative thereto about an axis parallel with said axes, a kerf cutter having motor operated swinging means and pivotally mounted on said cutter support to swing in a vertical plane relative thereto about a horizontal axis, said first support being swingable relative to said supporting structure while the latter remains stationary as regards swinging movement about its own axis relative to said base, and motor operated, operator controlled means for swinging

said first support relative to said supporting structure and for swinging said cutter support relative to said first support, said cutter support being swingable relative to said first support while the latter remains stationary as regards swinging movement about its own axis. 5

9. In a mining apparatus, a portable base, a supporting structure mounted on said base to swing horizontally relative thereto, a support mounted on said supporting structure to rotate relative thereto about a horizontal axis, a second support mounted on said first support to swing relative thereto about an axis at right angles to the axis of said first support, a kerf cutter support pivotally mounted on the outer extremity of said second support to swing relative thereto about an axis parallel with the axis of said second support, a kerf cutter pivotally mounted on said third support, and motor operated, operator controlled means for swinging said cutter support relative to said second support while the latter remains stationary as regards swinging movement about its own axis. 10

10. In a mining apparatus, a portable base, a supporting structure mounted on said base to swing horizontally relative thereto, a support mounted on said supporting structure to rotate relative thereto about a horizontal axis, a second support mounted on said first support to swing relative thereto about an axis at right angles to the axis of said first support, a kerf cutter support pivotally mounted on the outer extremity of said second support to swing relative thereto about an axis parallel with the axis of said second support, a kerf cutter pivotally mounted on said third support, and motor operated, operator controlled means for independently swinging said second and third supports about their respective axes. 15

11. In a mining apparatus, a portable base, a supporting structure mounted on said base to swing horizontally relative thereto, a support mounted on said supporting structure to rotate relative thereto about a horizontal axis, a second support mounted on said first support to swing relative thereto about an axis at right angles to the axis of said first support, a kerf cutter support pivotally mounted on the outer extremity of said second support to swing relative thereto about an axis parallel with the axis of said second support, a kerf cutter pivotally mounted on said third support, and motor operated, operator controlled means for independently swinging said second and third supports about their respective axes, said third support being swingable relative to said second support while the latter remains stationary. 20

12. In a mining apparatus, a portable base, a supporting structure mounted on said base to swing horizontally relative thereto, a support mounted on said supporting structure to rotate relative thereto about a horizontal axis, a second support mounted on said first support to swing relative thereto about an axis at right angles to the axis of said first support, a kerf cutter support pivotally mounted on the outer extremity of said second support to swing relative thereto about an axis parallel with the axis of said second support, a kerf cutter pivotally mounted on said third support, and motor operated, operator controlled means for independently swinging said second and third supports about their respective axes, said second support being swingable relative to said first support while the latter remains stationary. 25

13. In a mining apparatus, a portable base, a supporting structure mounted on said base to swing horizontally relative thereto, a support mounted on said supporting structure to rotate relatively thereto about a horizontal axis, a second support mounted on said first support to swing relatively thereto about an axis at right angles to the axis of said first support, a kerf cutter support pivotally mounted on the outer extremity 5 of said second support to swing relatively thereto about an axis parallel with the axis of said second support, a kerf cutter pivotally mounted on said third support, and motor operated, operator controlled means for independently swinging said second and third supports about their respective axes, said third support being swingable relative to said second support while the latter remains stationary and said second support being swingable relative to said first support while the latter remains stationary. 10
14. In a mining apparatus, a portable base, a horizontal turntable mounted on said base to swing relatively thereto about a vertical axis, a single arm pivotally mounted on said turntable to swing relatively thereto about a parallel axis, a kerf cutter support pivotally mounted on the outer extremity of said arm to swing relatively thereto about an axis parallel with said axes, said arm constituting the sole swingable supporting connection between the turntable and cutter support, and a kerf cutter pivotally mounted on said cutter support to swing in a vertical plane relative thereto about a horizontal axis. 15
15. In a mining apparatus, a portable base, a horizontal turntable mounted on said base to swing relatively thereto about a vertical axis, a single arm pivotally mounted on said turntable to swing relatively thereto about a parallel axis, a kerf cutter support pivotally mounted on the outer extremity of said arm to swing relatively thereto about an axis parallel with said axes, said arm constituting the sole swingable supporting connection between the turntable and cutter support, and a kerf cutter pivotally mounted on said cutter support to swing in a vertical plane relatively thereto about a horizontal axis, said cutter support being swingable about its axis relative to said arm while the latter remains stationary. 20
16. In a mining apparatus, a portable base, a horizontal turntable mounted on said base to swing relatively thereto about a vertical axis, a single arm pivotally mounted on said turntable to swing relatively thereto about a parallel axis, a kerf cutter support pivotally mounted on the outer extremity of said arm to swing relatively thereto about an axis parallel with said axes, said arm constituting the sole swingable supporting connection between the turntable and cutter support, and a kerf cutter pivotally mounted on said cutter support to swing in a vertical plane relative thereto about a horizontal axis, said arm being swingable about the turntable axis relative to the base and said cutter support being independently swingable relative to said arm during swinging of said arm about the turntable axis. 25
17. In a mining apparatus, a portable base, a horizontal turntable mounted on said base to swing relatively thereto about a vertical axis, a cutter head mounted on said turntable to rotate relatively thereto about a horizontal axis, a single arm pivotally mounted on said cutter head to swing relatively thereto about an axis at right angles to the cutter head axis, a kerf cutter sup- 30 port pivotally mounted on the outer extremity of said arm to swing relatively thereto about an axis parallel with said arm axis, said arm constituting the sole supporting connection between the cutter head and cutter support, and a kerf cutter pivotally mounted on said cutter support to swing relatively thereto about an axis at right angles to a line parallel to a line parallel to said cutter support axis, said cutter support being swingable about its axis relative to said arm while the latter remains stationary. 35
18. In a mining apparatus, a portable base, a horizontal turntable mounted on said base to swing relatively thereto about a vertical axis, a cutter head mounted on said turntable to rotate relatively thereto about a horizontal axis, a single arm pivotally mounted on said cutter head to swing relatively thereto about an axis at right angles to the cutter head axis, a kerf cutter support pivotally mounted on the outer extremity of said arm to swing relatively thereto about an axis parallel with said arm axis, said arm constituting the sole supporting connection between the cutter head and cutter support, and a kerf cutter pivotally mounted on said cutter support to swing relatively thereto about an axis at right angles to a line parallel to a line parallel to said cutter support axis, said cutter support being swingable about its axis relative to said arm while the latter remains stationary. 40
19. In a mining apparatus, a portable base, a horizontal turntable mounted on said base to swing relatively thereto about a vertical axis, a cutter head mounted on said turntable to rotate relatively thereto about a horizontal axis, a single arm pivotally mounted on said cutter head to swing relatively thereto about an axis at right angles to the cutter head axis, a kerf cutter support pivotally mounted on the outer extremity of said arm to swing relatively thereto about an axis parallel with said arm axis, said arm constituting the sole supporting connection between the cutter head and cutter support, and a kerf cutter pivotally mounted on said cutter support to swing relatively thereto about an axis at right angles to a line parallel to a line parallel to said cutter support axis, said cutter support being swingable about its axis relative to said arm while the latter remains stationary, said arm being swingable about the turntable axis relative to the base and said cutter support being independently swingable relative to said arm during swinging of said arm about the turntable axis. 45
20. In a mining apparatus, a portable base, a horizontal turntable mounted on said base for rotation about a vertical axis relatively thereto, a cutter head mounted on said turntable to rotate relatively thereto about an axis extending radially with respect to the axial line of the turntable, an arm pivotally mounted on said cutter head to swing relatively thereto about an axis at right angles to the head axis, a kerf cutter support pivotally mounted on the outer extremity of said arm to swing relatively thereto about an axis parallel to the arm axis, and a kerf cutter pivotally mounted on said cutter support to swing relatively thereto about an axis at right angles to a line parallel to a line parallel to the axis of said cutter support, said turntable being rotatable and said arm and cutter support being swingable to move the kerf cutter into parallel cutting positions to cut parallel vertical kerfs between the ribs of the entry including kerfs spaced more widely than the maximum range of arm swing alone permits. 50
21. In a mining apparatus, a portable base, a kerf cutter, and an adjustable supporting struc- 55
- 60
- 65
- 70
- 75

ture for said kerf cutter adjustable to position the same in a plurality of parallel planes within certain limits and in other parallel planes outside said limits, said supporting structure including 5 supporting elements adjustable relative to the base about parallel axes spaced longitudinally of said base, said kerf cutter adjustable upon adjustment about the front axis into parallel cutting positions to cut parallel kerfs within certain 10 limits and adjustable upon adjustment about the rear axis into parallel cutting positions parallel with aforesaid cutting positions to cut parallel kerfs outside of said limits.

22. In a mining apparatus, a portable base, a 15 kerf cutter, and an adjustable supporting structure for said kerf cutter adjustable to position the same in a plurality of parallel planes within certain limits and in other parallel planes outside said limits, said supporting structure including 20 supporting elements adjustable relative to the base about parallel axes spaced longitudinally of said base, said kerf cutter adjustable upon adjustment about the front axis into parallel cutting positions to cut parallel kerfs within certain 25 limits and adjustable upon adjustment about the rear axis into parallel cutting positions parallel with aforesaid cutting positions to cut parallel kerfs outside of said limits, said supporting structure also including means for supporting the kerf 30 cutter for adjustment about a longitudinal axis into horizontal and vertical cutting positions.

23. In a mining apparatus, a portable base, a kerf cutter, and an adjustable supporting structure for said kerf cutter adjustable to position the same in a plurality of parallel planes within 35 certain limits and in other parallel planes outside said limits, said supporting structure including supporting elements adjustable relative to the base about parallel axes spaced longitudinally of 40 said base, said kerf cutter adjustable upon adjustment about the front axis into parallel cutting positions to cut parallel kerfs within certain limits and adjustable upon adjustment about the rear axis into parallel cutting positions parallel with 45 aforesaid cutting positions to cut parallel kerfs outside of said limits, said supporting structure also including means for supporting the kerf cutter for adjustment about a longitudinal axis extending radially from said rear axis to move 50 the kerf cutter into horizontal and vertical cutting positions.

24. In a mining apparatus, a portable base, a kerf cutter, and an adjustable supporting structure for said kerf cutter adjustable to position the same in a plurality of parallel planes within 55 certain limits and in other parallel planes outside said limits, said supporting structure including supporting elements adjustable relative to the base about parallel axes spaced longitudinally of 60 said base, said kerf cutter adjustable upon adjustment about the front axis into parallel cutting positions to cut parallel kerfs within certain limits and adjustable upon adjustment about the rear axis into parallel cutting positions parallel with 65 aforesaid cutting positions to cut parallel kerfs outside of said limits, said supporting structure also including means for adjusting the kerf cutter into a position to cut a horizontal kerf at the level of the mine bottom.

70 25. In a mining apparatus, a portable base, a kerf cutter, and an adjustable supporting structure for said kerf cutter adjustable to position the same in a plurality of parallel planes within certain limits and in other parallel planes outside 75 said limits, said supporting structure including

supporting elements adjustable relative to the base about parallel axes spaced longitudinally of said base, said kerf cutter adjustable upon adjustment about the front axis into parallel cutting positions to cut parallel kerfs within certain 5 limits and adjustable upon adjustment about the rear axis into parallel cutting positions parallel with aforesaid cutting positions to cut parallel kerfs outside of said limits, said supporting structure also including means for adjusting the kerf cutter into a position to cut a horizontal kerf at the level of the mine bottom outside the path of movement of the base and in advance of said base.

26. In a mining apparatus, a portable base, a 15 kerf cutter, and an adjustable supporting structure for said kerf cutter including supporting elements swingable horizontally relative to the base about parallel axes spaced longitudinally of the base and for adjusting the kerf cutter into horizontal and shearing positions about an axis extending radially from the rear axis of horizontal swinging movement, said kerf cutter adjustable upon adjustment about the forward axis of horizontal swinging movement into positions 25 to cut parallel kerfs within certain limits and adjustable upon adjustment about the rear axis of horizontal swinging movement into positions to cut parallel kerfs parallel with aforesaid kerfs and outside of said limits whereby the cutting 30 range of the kerf cutter is extended.

27. In a mining apparatus, a portable base, a shearing kerf cutter, and an adjustable supporting structure for said kerf cutter including supporting elements adjustable about parallel axes 35 spaced longitudinally of said base, said kerf cutter adjustable upon adjustment about the front axis into parallel shear cutting positions within certain limits and adjustable upon adjustment about the rear axis into parallel shear cutting 40 positions parallel to said first mentioned positions and outside of said limits and at either side of the base whereby the shearing range of the kerf cutter is extended.

28. In a mining apparatus, a portable base, a 45 kerf cutter, and an adjustable supporting structure for said kerf cutter, said supporting structure including supporting elements adjustable relative to the base about parallel axes spaced longitudinally of the base, said kerf cutter adjustable upon adjustment about the front axis into parallel cutting positions to cut parallel 50 kerfs within certain limits within the sides of said base and beyond the sides of said base, said kerf cutter adjustable upon adjustment about the rear axis into parallel cutting positions parallel with aforesaid cutting positions to cut parallel kerfs outside of said limits and beyond the outermost range of aforesaid adjustment about said front axis.

29. In a mining apparatus, a portable base, a shearing kerf cutter, and an adjustable supporting structure for said kerf cutter including a supporting element adjustable about parallel axes spaced longitudinally of said base, said kerf cutter adjustable upon adjustment about the front axis into parallel shear cutting positions within certain limits between the sides of said base and beyond the sides of said base, said kerf cutter adjustable upon adjustment about the rear axis into parallel shear cutting positions parallel to said first mentioned positions and outside of said limits beyond the outermost limits of adjustment about said front axis whereby the shearing range of the kerf cutter is extended.

30. In a mining apparatus, a portable base, a kerf cutter, and an adjustable supporting structure for said kerf cutter, said supporting structure including supporting elements adjustable relative to the base about parallel vertical axes spaced longitudinally of the base, said kerf cutter adjustable upon adjustment about the front axis into parallel cutting positions to cut parallel kerfs within certain limits within the sides of said base and beyond the sides of said base, said kerf cutter adjustable upon adjustment about the rear axis into parallel cutting positions to cut parallel kerfs outside of said limits and beyond the outermost range of aforesaid adjustment about said front axis.
31. In a mining apparatus, a portable base, a shearing kerf cutter, and an adjustable supporting structure for said kerf cutter including supporting elements adjustable about parallel vertical axes spaced longitudinally of said base, said kerf cutter adjustable upon adjustment about the front axis into parallel shear cutting positions within certain limits between the sides of said base and beyond the sides of said base, said kerf cutter adjustable upon adjustment about the rear axis into parallel shear cutting positions parallel to said first mentioned positions and outside of said limits beyond the outermost limits of adjustment about said front axis whereby the shearing range of the kerf cutter is extended.
32. In a mining apparatus, a portable base, a kerf cutter, and an adjustable supporting structure for said kerf cutter, said supporting structure including supporting elements adjustable relative to the base about parallel vertical axes spaced longitudinally of the base, the rearmost of said axes lying in the longitudinal vertical center of the machine, said kerf cutter adjustable upon adjustment about the front axis into parallel cutting positions to cut parallel kerfs within certain limits within the sides of said base and beyond the sides of said base, said kerf cutter adjustable upon adjustment about the rear axis in parallel cutting positions parallel with aforesaid cutting positions to cut parallel kerfs outside of said limits and beyond the outermost range of aforesaid adjustment about said front axis.
33. In a mining apparatus, a portable base, a shearing kerf cutter, and an adjustable supporting structure for said kerf cutter including supporting elements adjustable about parallel vertical axes spaced longitudinally of said base, the rearmost of said axes lying in the longitudinal vertical center of the machine, said kerf cutter adjustable upon adjustment about the front axis into parallel shear cutting positions within certain limits between the sides of said base and beyond the sides of said base, said kerf cutter adjustable upon adjustment about the rear axis into parallel shear cutting positions parallel to said first mentioned positions and outside of said limits beyond the outermost limits of adjustment about said front axis whereby the shearing range of the kerf cutter is extended.
34. In a mining apparatus, a portable base, a horizontal turntable on said base, a support mounted on said base for rotation relative thereto about a horizontal axis extending radially with respect to the turntable axis, an arm pivotally mounted on said support to swing relative thereto about an axis at right angles to the support axis, a second support pivotally mounted on the outer extremity of said arm to swing relative thereto about an axis parallel with the arm
35. In a mining apparatus, a portable base, a horizontal turntable on said base, a support mounted on said base for rotation relative thereto about a horizontal axis extending radially with respect to the turntable axis, an arm pivotally mounted on said support to swing relative thereto about an axis at right angles to the support axis, a second support pivotally mounted on the outer extremity of said arm to swing relative thereto about an axis parallel with the arm pivot axis, a kerf cutter pivotally mounted on said second support to swing relative thereto about an axis at right angles to a line parallel to the axis of said second support, said kerf cutter being swingable with said second support through a relatively wide range while the arm remains stationary as regards swinging movement about its own axis.
36. In a mining apparatus, a portable base, a horizontal turntable on said base, a support mounted on said base for rotation relative thereto about a horizontal axis extending radially with respect to the turntable axis, an arm pivotally mounted on said support to swing relative thereto about an axis at right angles to the support axis, a second support pivotally mounted on the outer extremity of said arm to swing relative thereto about an axis parallel with the arm pivot axis, a kerf cutter pivotally mounted on said second support to swing relative thereto about an axis at right angles to a line parallel to the axis of said second support, and a motor on said turntable for rotating said first support, for swinging said arm relative to said first support, for swinging said second support relative to said arm while the latter is stationary and for swinging said kerf cutter about its pivot.
37. In a mining apparatus, a portable base, a horizontal turntable on said base, mechanism for adjusting said turntable into different elevated positions relative to the base, a support mounted on said turntable for rotation relative thereto about an axis extending radially with respect to the turntable axis, an arm pivotally mounted on said support to swing relative thereto about an axis at right angles to said support axis, a second support pivotally mounted on the outer extremity of said arm to swing relative thereto independently thereof about an axis parallel with the arm pivot axis, and a kerf cutter pivotally mounted on said second support to swing relative thereto about an axis at right angles to a line parallel to the axis of said second support.
38. In a mining apparatus, a portable base, a horizontal turntable on said base, mechanism for adjusting said turntable into different elevated positions relative to the base, a support mounted on said turntable for rotation relative thereto about an axis extending radially with respect to the turntable axis, an arm pivotally mounted on said support to swing relative thereto about an axis at right angles to said support axis, a second support pivotally mounted on

totally mounted on said support to swing relative thereto about an axis at right angles to said support axis, a second support pivotally mounted on the outer extremity of said arm to swing relative thereto about an axis parallel with the arm pivot axis, a kerf cutter pivotally mounted on said second support to swing relative thereto about an axis at right angles to a line parallel to a line parallel to the axis of said second support, 10 and a motor on said turntable for rotating said turntable relative to the base, for rotating said first support relative to the turntable, for swinging said second support relative to said arm independently of swing of the latter and for swinging said kerf cutter about its pivot relative to said second support.

46. In a mining apparatus, a portable base, a shearing kerf cutter, and an adjustable supporting structure for said kerf cutter including supporting elements adjustable about parallel axes spaced longitudinally of the base, said kerf cutter adjustable upon adjustment about the front axis into parallel shear cutting positions between the sides of the base and beyond the sides of the base, 20 said kerf cutter adjustable upon adjustment about the rear axis into parallel shear cutting positions parallel to said first mentioned positions and outside of said limits, said kerf cutter adjustable to cut parallel shearing kerfs at either rib of an entry of a width equal to more than twice the width of the apparatus.

47. In a mining apparatus, a portable base, a frame overlying said base and swingable horizontally relative thereto about a vertical axis, said 25 frame overhanging the forward end of said base, a support pivotally mounted on the outer overhanging extremity of said frame to swing horizontally relative thereto about an axis parallel with the frame axis, a cutter support pivotally mounted on the outer extremity of said first support to swing relative thereto about an axis parallel with the support axis, a kerf cutter pivotally mounted on said second support to swing relative thereto about an axis at right angles to a line parallel to a line parallel to the axis of said second support, and motor operated devices for swinging said frame relative to the base, for swinging said first support relative to said frame, for swinging said second support relative to said first support and for swinging said kerf cutter relative to said second support, said first support being swingable relative to said frame while the latter remains stationary and said second support being swingable relative to said first support while said first support remains stationary.

48. In a mining apparatus, a portable base, a frame overlying said base and swingable horizontally relative thereto about a vertical axis, said frame overhanging the forward end of said base, a support pivotally mounted on the outer overhanging extremity of said frame to swing horizontally relative thereto about an axis parallel with the frame axis, a cutter support pivotally mounted on the outer extremity of said first support to swing relative thereto about an axis parallel with the support axis, a kerf cutter pivotally mounted on said second support to swing relative thereto about an axis at right angles to a line parallel to a line parallel to the axis of said second support, and motor operated devices for swinging said frame relative to the base, for swinging said first support relative to said frame, for swinging said second support relative to said first support and for swinging said kerf cutter relative to said second support, said first support being swingable

relative to said frame while the latter remains stationary and said second support being swingable relative to said first support while said first support remains stationary, said motor operated devices including a motor mounted on said swingable frame.

5

49. In a mining apparatus, a portable base, a frame structure mounted on said base to swing horizontally relative thereto, a support mounted on said frame structure for rotation relative thereto about a horizontal axis, an arm structure pivotally mounted on said rotatable support to swing relative thereto, a cutter support pivotally mounted on said arm structure, a kerf cutter pivotally mounted on said cutter support, and a motor relative to which said arm structure is swingable for swinging said arm structure, for swinging said cutter support relative to said arm structure and for swinging said kerf cutter, said cutter support being swingable relative to said arm structure while the latter remains stationary as regards swinging movement about its own axis.

50. In a mining apparatus, a portable base, a frame structure mounted on said base to swing horizontally relative thereto, a support mounted on said frame structure for rotation relative thereto about a horizontal axis, an arm structure pivotally mounted on said rotatable support to swing relative thereto, a cutter support pivotally mounted on said arm structure, a kerf cutter pivotally mounted on said cutter support, and a motor mounted on said swingable frame structure and relative to which said arm structure is swingable for swinging said arm structure, for swinging said cutter support relative to said arm structure while the latter is stationary and for swinging said kerf cutter.

51. In a mining apparatus, a portable base, a frame structure mounted on said base to swing horizontally relative thereto, a support mounted on said frame structure for rotation relative thereto about a horizontal axis, an arm structure pivotally mounted on said rotatable support to swing relative thereto, a cutter support pivotally mounted on said arm structure, a kerf cutter pivotally mounted on said cutter support, and a motor mounted on said swingable frame structure and relative to which said arm structure is swingable for swinging said arm structure, for swinging said cutter support relative to said arm structure and for swinging said kerf cutter, said cutter support being swingable relative to said arm structure while the latter remains stationary as regards swinging movement about its own axis.

55

52. In a mining apparatus, a portable base, a frame structure mounted on said base to swing horizontally relative thereto, a support mounted on said frame structure for rotation relative thereto about a horizontal axis, an arm structure pivotally mounted on said rotatable support to swing relative thereto, a cutter support pivotally mounted on said arm structure, a kerf cutter pivotally mounted on said cutter support, and a motor mounted on said swingable frame structure and relative to which said arm structure is swingable for swinging said arm structure, for swinging said cutter support relative to said arm structure and for swinging said kerf cutter, said cutter support being swingable relative to said arm structure while the latter remains stationary as regards swinging movement of the latter and for swinging said kerf cutter.

60

53. In a mining apparatus, a portable base, a frame structure mounted on said base and extending forwardly in advance of said base, and a kerf cutter support pivotally mounted on the

75

outer extremity of said frame structure, said frame structure including articulated supporting elements swingable simultaneously about a common axis to move the cutter support through a 5 relatively wide range of adjustment and one supporting element swingable relative to the other about a different axis to move the cutter support through a relatively restricted range of adjustment, and devices for swinging said cutter support relative to said frame structure to maintain the kerf cutter in parallel cutting positions during either adjustment of said frame structure.

54. In a mining apparatus, a portable base, a frame structure mounted on said base and extending forwardly in advance of said base, and a kerf cutter support pivotally mounted on the outer extremity of said frame structure, said frame structure including articulated supporting elements swingable simultaneously about a common axis to move the cutter support through a relatively wide range of adjustment and one supporting element swingable relative to the other about a different axis to move the cutter support through a relatively restricted range of adjustment, and devices for swinging said cutter support relative to said frame structure to maintain the kerf cutter in parallel cutting positions during either adjustment of said frame structure, one of said supporting elements pivotally connected 30 to the other about a horizontal axis whereby one supporting element may be swung relative to the other to move the cutter support into horizontal and vertical cutting positions.

55. In a mining apparatus, a portable base, a horizontal turntable on said base, a kerf cutter, and an adjustable supporting structure adjustable about a radial horizontal axis relative to said turntable and intervening said turntable and kerf cutter, said supporting structure including but a 40 single arm hinged to said turntable at the forward end of said base to swing about an axis at right angles to a line extending radially from the turntable axis and on which the kerf cutter is pivotally mounted, said arm constituting the sole supporting connection between the kerf cutter and said turntable, and mechanism for adjusting said supporting structure to position said kerf cutter into parallel planes, said adjusting mechanism including means for swinging said arm about its 50 pivot to move said kerf cutter into aforesaid parallel planes.

56. In a mining apparatus, a portable base, a horizontal turntable on said base, a kerf cutter, and an adjustable supporting structure adjustable about a radial horizontal axis relative to said turntable and intervening said turntable and kerf cutter, said supporting structure including but a single arm hinged to said turntable at the forward end of said base to swing about an axis at right angles to a line extending radially from the turntable axis and on which the kerf cutter is pivotally mounted, said arm constituting the sole supporting connection between the kerf cutter and said turntable, and mechanism for adjusting said supporting structure to position said kerf cutter into parallel planes adjacent the mine floor and parallel planes a substantial distance above the top of said turntable, said adjusting mechanism including means for swinging said arm about its pivot to move said kerf cutter into aforesaid parallel planes.

57. In a mining apparatus, a portable base, a horizontal turntable on said base, an arm pivotally mounted on said turntable to swing in a

vertical direction relative thereto about an axis transverse to a line extending radially from the turntable axis, a cutter support pivotally mounted on the outer extremity of said arm to swing relative thereto about an axis parallel with the arm pivot axis, a horizontal kerf cutter mounted on said cutter support, said cutter support swingable about its pivot relative to said arm to move said kerf cutter into relatively inclined cutting planes, means for swinging said arm relative to said turntable and said cutter support relative to said arm to move said kerf cutter into parallel horizontal planes including horizontal planes above and below said turntable while the kerf cutter at all times remain in a horizontal cutting position, and means for adjusting said arm relative to said turntable to move said kerf cutter in a vertical cutting position.

58. In a mining apparatus, a portable base, a horizontal turntable on said base, an arm pivotally mounted on said turntable to swing in a vertical direction relative thereto about an axis transverse to a line extending radially from the turntable axis, a cutter support pivotally mounted on the outer extremity of said arm to swing relative thereto about an axis parallel with the arm pivot axis, a horizontal kerf cutter mounted on said cutter support, said cutter support swingable about its pivot relative to said arm to move said kerf cutter into relatively inclined cutting planes, means for swinging said arm relative to said turntable and cutter support relative to said arm to move said kerf cutter into parallel horizontal planes including horizontal planes adjacent the mine floor and horizontal planes a substantial distance above the top of said turntable while the kerf cutter at all times remains in a horizontal cutting position, and means for adjusting said arm relative to said turntable to move said kerf cutter into a vertical cutting position.

59. In a mining apparatus, a portable base, a horizontal turntable on said base, an arm pivotally mounted on said base to swing in a vertical direction relative thereto about an axis transverse to a line extending radially from the turntable axis, said arm extending longitudinally of the base a substantial distance in advance of the base, a cutter support pivotally mounted on the outer extremity of said arm to swing relative thereto about an axis parallel with the arm pivot axis, said cutter support being swingable through at least 90° relative to said arm, a kerf cutter mounted on said cutter support, said cutter support swingable about its pivot relative to said arm to move said kerf cutter into relatively inclined cutting planes, means for swinging said arm and support about their respective axes, and means for adjusting said arm relative to said turntable to move said kerf cutter into a vertical cutting position.

60. In a mining apparatus, a portable base, a horizontal turntable on said base, an arm pivotally mounted on said base to swing in a vertical direction relative thereto about an axis transverse to a line extending radially from the turntable axis, said arm extending longitudinally of the base a substantial distance in advance of the base, a cutter support pivotally mounted on the outer extremity of said arm to swing relative thereto about an axis parallel with the arm pivot axis, said cutter support being swingable through substantially 180° relative to said arm, a kerf cutter mounted on said cutter support, said cutter support swingable about its pivot

relative to said arm to move said kerf cutter into relatively inclined cutting planes, means for swinging said arm and support about their respective axes, and means for adjusting said arm relative to said turntable to move said kerf cutter into a vertical cutting position.

61. In a mining apparatus, a portable base, a horizontal turntable mounted on said base, a support mounted on said turntable for rotation about an axis extending radially from the turntable axis, an arm structure pivotally mounted on said rotatable support to swing relative thereto about an axis transverse to the support axis, a cutter frame mounted on the outer extremity of said arm structure and to which the arm structure is pivotally connected, a kerf cutter carried by said cutter frame, and means for rotating said rotatable support to move the arm structure and cutter frame about the axis of said rotatable support to adjust the kerf cutter into horizontal and vertical cutting positions, means for swinging said arm structure while said rotatable support remains stationary as to rotation about its own axis to move the kerf cutter bodily through a series of parallel cutting positions, from a point at a substantial distance to one side of said rotatable support axis to a point at a substantial distance to the other side of said rotatable support axis.

62. In a mining apparatus, a portable base, a horizontal turntable mounted on said base, a support mounted on said turntable for rotation about an axis extending radially from the turntable axis, an arm structure pivotally mounted on said rotatable support to swing relative thereto about an axis transverse to the support axis, a cutter frame mounted on the outer extremity of said arm structure and to which the arm structure is pivotally connected, a kerf cutter carried by said cutter frame, and means for rotating said rotatable support to move the arm structure and cutter frame about the axis of said rotatable support to adjust the kerf cutter into horizontal and vertical cutting positions, means for swinging said arm structure while said rotatable support remains stationary as to rotation about its own axis to move the kerf cutter bodily through a series of parallel cutting positions, from a point at a substantial distance to one side of said rotatable support axis to a point at a substantial distance to the other side of said rotatable support axis, said kerf cutter moving through the plane parallel to said cutting positions and in which said support axis lies during adjustment thereof from one side of said support axis to the other.

63. In a mining apparatus, a portable base, a horizontal turntable on said base, kerf cutting mechanism including a cutter support, and an adjustable supporting structure rotatable about a radial horizontal axis relative to said turntable and intervening said turntable and cutter support, said supporting structure including an arm pivotally connected to the turntable and on which the cutter support is pivotally mounted, said arm and support being swingable about parallel axes lying in planes parallel to a plane including the turntable axis to move the kerf cutter into parallel planes, motor operated devices for swinging said arm about its pivot relative to said turntable, and separate motor operated devices for swinging said cutter support about its pivot relative to said arm whereby said arm may be swung without swinging of said cutter support relative thereto.

64. In a mining apparatus, a portable base, a horizontal turntable on said base, kerf cutting mechanism including a cutter support, and an adjustable supporting structure rotatable about a radial horizontal axis relative to said turntable and intervening said turntable and cutter support, said supporting structure including an arm pivotally connected to the turntable and on which the cutter support is pivotally mounted, said arm and support being swingable about parallel axes lying in planes parallel to a plane including the turntable axis to move the kerf cutter into parallel planes, motor operated devices for swinging said arm about its pivot relative to said turntable, and separate motor operated devices for swinging said cutter support about its pivot relative to said arm, said means for swinging said cutter support relative to said arm being operable independently of said arm swinging means.

65. In a mining apparatus, a wheeled truck adapted to run along a mine trackway, a horizontal turntable on said truck, an arm pivotally mounted on the turntable at the forward end of said truck to swing in a vertical direction relative thereto about a horizontal axis lying in a plane parallel to a plane including the turntable axis and in advance of the front truck wheel axes, a cutter support pivotally mounted on the outer extremity of said arm, a horizontal kerf cutter carried by said cutter support, motor operated means for swinging said kerf cutter support about its pivot relative to said arm to move said kerf cutter into relatively inclined cutting planes and for swinging said arm and cutter support about their respective axes to move the kerf cutter while the cutting plane of the latter remains parallel to a single plane into parallel horizontal planes including horizontal planes above and below said turntable and means for adjusting said arm into a position to swing in a horizontal direction relative to said turntable.

66. In a mining apparatus, a wheeled truck adapted to run along a mine trackway, a horizontal turntable on said truck, an arm pivotally mounted on the turntable at the forward end of said truck to swing in a vertical direction relative thereto about a horizontal axis lying in a plane parallel to a plane including the turntable axis and in advance of the front truck wheel axes, a cutter support pivotally mounted on the outer extremity of said arm, a horizontal kerf cutter carried by said cutter support, motor operated means for swinging said kerf cutter support about its pivot relative to said arm to move said kerf cutter into relatively inclined cutting planes and for swinging said arm and cutter support about their respective axes to move the kerf cutter while the latter remains at all times in horizontal cutting position into parallel horizontal planes including horizontal planes adjacent the mine floor and horizontal planes a substantial distance above the top of said turntable and means for adjusting said arm into a position to swing in a horizontal direction relative to said turntable.

67. In a mining apparatus, a portable base, a horizontal turntable on said base, an arm pivotally mounted on said turntable to swing in a vertical direction in planes extending radially from the turntable axis, a kerf cutter support pivotally mounted on the outer extremity of said arm to swing relative thereto and independently of arm swing about an axis parallel with the arm pivot axis, a kerf cutter mounted on said cutter

support, means for adjusting said arm into a position to swing horizontally relative to said turntable, and a motor on said turntable relative to which said arm is swingable for swinging 5 said arm relative to said turntable and for actuating said kerf cutter.

68. In a mining apparatus, a portable base, a horizontal turntable on said base, an arm pivotally mounted on said turntable to swing in a 10 vertical direction in planes extending radially from the turntable axis, means for adjusting said

arm relative to the turntable into a position to swing horizontally relative to said turntable, a cutter support pivotally mounted on the outer extremity of said arm to swing relative thereto about an axis parallel to the arm pivot axis, a kerf cutter mounted on the cutter support, and motor operated means for independently swinging said arm and cutter support about their respective pivots. 5

CHARLES F. OSGOOD. 10

CERTIFICATE OF CORRECTION.

July 9, 1935.

Patent No. 2,007,908.

CHARLES F. OSGOOD.

It is hereby certified that error appears in the printed specification of the above numbered patent requiring correction as follows: Page 9, first column, lines 5, 7, 10, 36, 38, 40, 45, 52, 54, 56, 70, 72 and 74, and second column, lines 2, 8, 12, 14, 19, 24, 31, 33, 35, 38, 43, 54, 56, 59, 62 and 64, claims 13, 15, 16, 17, 18, 19 and 20 respectively, for "relatively" read relative; page 14, second column, line 15, claim 57, for "remain" read remains; and same claim, line 20, for "in" read into; and that the said Letters Patent should be read with these corrections therein that the same may conform to the record of the case in the Patent Office.

Signed and sealed this 24th day of September, A. D. 1935.

Leslie Frazer

Acting Commissioner of Patents.
